United States Patent Office

Des. 219,147
Patented Nov. 10, 1970

219,147

ELECTRICAL BUSHING OR SIMILAR ARTICLE

Richard F. Propst, Pittsfield, Mass., assignor to General Electric Company, a corporation of New York

Filed July 17, 1969, Ser. No. 18,244

Term of patent 14 years

Int. Cl. D13—03

U.S. Cl. D26—10

FIG. 1 is a side elevation view of an electrical bushing or similar article showing my new design, the opposite side being substantially a mirror image thereof;

FIG. 2 is an end elevation view, showing the bottom end thereof;

FIG. 3 is an end elevation view, showing the top end thereof.

I claim:

The ornamental design of an electrical bushing or similar article, as shown and described.
